UNITED STATES PATENT OFFICE.

JOHN WILLISON, OF DERBY, ENGLAND, ASSIGNOR TO THE NATIONAL MALLEABLE CASTINGS COMPANY, OF CLEVELAND, OHIO, A CORPORATION OF OHIO.

CAR-COUPING.

1,229,367.

Specification of Letters Patent. Patented June 12, 1917.

Application filed October 8, 1914. Serial No. 865,633.

To all whom it may concern:

Be it known that I, JOHN WILLISON, a subject of the King of Great Britain, residing at Derby, county of Derby, England, 5 have invented new and useful Improvements in Car-Couplings, of which the following is a specification, reference being had to the accompanying drawings, in which—

Figure 1 is a plan of a car coupler embodying my invention arranged so as to intercouple with a coupler of the Master Car Builders' type and with the parts in locked position; Fig. 2 is a side elevation thereof; Fig. 3 is a plan similar to Fig. 1 with the 15 parts in knuckle thrown position, and Fig. 4 is a side elevation thereof; Fig. 5 is a plan showing the knuckle swung out of operative position, and Fig. 6 is an elevation thereof; Fig. 7 is a section on lines VII—VII of Fig. 2, and Figs. 8 and 9 are details of the lock and knuckle respectively.

My invention relates to car couplers of the rigid jawed type, such as are described and claimed in Letters Patent No. 1,201,665, is 25 sued to me on Oct. 17, 1916, which are designed to intercouple by a transverse movement of the opposing coupler-head and to be held in engagement with each other by the overlapping and interlocking of their 30 respective locking blocks. My invention consists in providing mechanism whereby a car coupler of such type, in addition to coupling with a coupler of its own type, may be readily intercoupled with a car coupler of 35 the Master Car Builders' or other similar type. My invention also consists in the construction and coöperation of the various parts which I shall hereinafter describe and claim.

40 Referring to the drawings A indicates the coupler head, B the lock and C the knuckle. The knuckle C is provided with two vertically disposed holes 2 and 3 for the alternative reception of the fulcrum or pivot pin 4. 45 The pivot pin hole 2 for the front fulcrum is formed through the hub 5 of the knuckle, and the pivot pin hole 3 for the rear fulcrum is formed in the rearward extension 6 of the knuckle. The left jaw 7 of the coupler head 50 A is bifurcated being comprised of the upper and lower portions 8 and 8^a and having a space intermediate of said portions of a size sufficient to receive the hub 5, the extension 6 and the tail 9 of the knuckle. 55 Through the upper and lower portions 8 and

8^a are the pivot pin holes 10, with which the hole 2 is adapted to be brought into register so that the pivot pin 4 may be inserted and the knuckle C thereby held in operative position. From the left side wall of the 60 coupler head project the apertured lugs 11 which are spaced apart sufficiently to permit the rear extension 6 to be swung between them and the hole 3 to be brought into register with the apertures in the lugs 11, in 65 which position the pin 4 may be inserted therethrough when it is desired to hold the knuckle in inoperative position.

The lock B operates in an inclined recess 12 in the central longitudinal plane of the 70 coupler head A and is provided with a forwardly and downwardly extending slot 13, which with the coöperating projection 14 on the coupler head controls the movement of the lock B in the recess 12. A stop 15 is 75 also provided on the side of lock which limits its downward movement either by contacting with the top of the knuckle tail when the knuckle is in use, or by contacting with the lower portion 8^a of the jaw 7 when 80 the knuckle is in inoperative position. The stop 15 thus prevents the lock from projecting forwardly of the contour line in front of the knuckle tail and from thus interfering with coupling with a coupler of the 85 Master Car Builders' type. In the recess 12 is an inclined guiding groove 16 with which the stop 15 coöperates when the lock B is sufficiently retracted.

When the coupler head A is to be used to 90 intercouple with a coupler of the Master Car Builders' type, the knuckle C is swung into the position shown in Fig. 3 with the hole 2 in register with the holes 10 of the portions 8 and 8^a and the pivot pin 4 is transferred 95 from the pin hole 3 to the pin hole 2 as shown. It is then in position for coupling. As the couplers come together, the knuckle tail will strike the forward face of the lock and drive it upwardly and rearwardly out 100 of the way, and will swing into closed position. The lock will then slide forwardly and downwardly by gravity into locked or lowermost position in front of the knuckle tail, as is best shown in Fig. 7. When in 105 operative position, the knuckle tail is prevented from swinging too far to the rear by the wall 17 at the rear of the space or cavity in the jaw 7, and from too great outward movement by the rear extension 6 which en- 110

gages the outer side wall of the jaw 7 as is shown in Fig. 3.

When the coupler head A is to be used to intercouple with a coupler of its own type the knuckle is rotated about its front fulcrum to bring the hole 3 into register with the apertures in the lug 11 and the pin 4 is withdrawn from its position in the holes 2 and 10 and inserted through the hole 3 and apertures in the lugs 11. The knuckle may then be swung rearwardly into the position shown in Fig. 5, in which it is inoperative and does not interfere with the normal operation of the coupler.

Various modifications may be made in the construction and operation of the coupler which I have hereinbefore shown and described, without departing from my invention.

20. What I claim is:

1. A car coupler adapted to intercouple with couplers of the Master Car Builders' type and of another type, said coupler comprising a head, a movable knuckle conforming to the Master Car Builders' contour, said coupler head having alternative fulcrums, said knuckle being adapted to pivot in one of said fulcrums when in operative position and in the other of said fulcrums when in inoperative position.

2. A car coupler adapted to intercouple with couplers of the Master Car Builders' type and of another type, said coupler comprising a head, and a movable knuckle conforming to the Master Car Builders' contour, the coupler head having a front fulcrum and a rear fulcrum, the knuckle being adapted to rotate about the front fulcrum when in operative position and about the rear fulcrum when in inoperative position.

3. A car coupler adapted to intercouple with couplers of the Master Car Builders' type and of another type, said coupler comprising a head, a movable knuckle, the coupler head having a bifurcated jaw in which the knuckle is adapted to seat, and a pivot pin to secure the knuckle in operative position in said jaw, the said knuckle being adapted, upon removal of the pivot pin, to be swung outwardly through said bifurcation into inoperative position.

4. A car coupler adapted to intercouple

with couplers of the Master Car Builders' type and of another type, said coupler comprising a head, and a movable knuckle, the 55 coupler head having a bifurcated jaw in which the knuckle is secured by a pivot pin when in operative position, said knuckle having also a rear extension upon which it is adapted to be moved out of operative position upon withdrawal of the pivot pin.

5. A car coupler adapted to intercouple with couplers of the Master Car Builders' type and of a different type, said coupler comprising a head, a knuckle pivoted to the 65 coupler head, and a gravity movable lock, said lock operating in a longitudinally-extending inclined recess and being adapted, when the knuckle has been swung into inoperative position by removal of the pivot pin, 70 to intercouple with a coupler of a different type by lateral movement and by overlapping of the locks.

6. A car coupler adapted to intercouple with couplers of the Master Car Builders' 75 type and of another type, said coupler comprising a head, and a movable knuckle conforming the Master Car Builders' contour, said knuckle in operative position being secured in and fulcrumed in the coupler head 80 by the usual pivot pin, and when in inoperative position being secured by a fulcrum to the rear of the first-named fulcrum and outside of the coupler head.

7. A car coupler adapted to intercouple 85 with couplers of the Master Car Builders' type and of another type, said coupler comprising a head and having a movable knuckle of the Master Car Builders' type, and a plurality of means on the knuckle for attaching 90 said knuckle to said head, one of said means forming a bearing for the mounting of said knuckle in operating position, and another of said means forming a point of attachment for securing said knuckle to the head in a 95 position removed from its operating position, either of said means being non-operating when the knuckle is attached by the other means.

JOHN WILLISON.
